UNITED STATES PATENT OFFICE.

HOWARD H. SHEELY, OF HUTCHINSON, KANSAS.

DESIGN FOR A PARING-KNIFE.

SPECIFICATION forming part of Design No. 30,674, dated May 2, 1899.

Application filed April 1, 1899. Serial No. 711,444. Term of patent 14 years.

To all whom it may concern:

Be it known that I, HOWARD H. SHEELY, a citizen of the United States, residing at Hutchinson, in the county of Reno, State of Kansas, have invented and produced a certain new and original Design for a Paring-Knife, of which the following is a specification, reference being had therein to the accompanying drawings.

Figure 1 is an elevation of a paring-knife, showing my design; and Fig. 2 is a vertical section through Fig. 1.

As shown in the drawings, the leading or material feature of my design consists of the curved outline A, provided at one side of the blade and beneath which straight lines B and C define the outline of an opening. The opposite side of the blade is shown as having a

straight outline D, similar straight outlines E being provided at the opposite ends of the line D. A knife-handle is shown of a substantially oval form, as indicated by the lines F, which terminate adjacent to the blade in straight lines F'.

Having described my invention, what I claim, and desire to secure by Letters Patent, is—

The design for a paring-knife as herein shown and described.

In testimony whereof I affix my signature in presence of two witnesses.

HOWARD H. SHEELY.
